UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,134, dated September 29, 1896.

Application filed August 24, 1896. Serial No. 603,792. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of an arrangement of leaves forming an all-over or tapestry-like effect, as represented in the accompanying drawing.

The border for the said design consists of a similar arrangement of leaves with sprays of flowers, as shown in the drawing.

What I claim is—

1. The design for wall-paper herein shown and described.

2. The design for wall-paper, the border 20 herein shown and described.

Witness my hand this 10th day of August, 1896.

CHARLES BOOZ.
